UNITED STATES PATENT OFFICE.

HENRY BENTON, OF ELIZABETHPORT, NEW JERSEY.

FURNACE GRATE.

Application filed February 24, 1921. Serial No. 447,523.

To all whom it may concern:

Be it known that I, HENRY BENTON, a citizen of the United States, and a resident of Elizabethport, in the county of Union and 5 State of New Jersey, have invented a new and Improved Furnace Grate, of which the following is a full, clear, and exact description.

My invention is an improvement on the 10 grate forming the subject matter of United States Patent No. 1,131,461, granted to me March 9th, 1915.

The general object of my present invention is to provide a grate of the type referred 15 to improved in various particulars.

The distinctive features of the invention will be referred to in connection with a description of the structural embodiment of the invention given hereinafter and will be 20 defined in the claims.

Reference is to be had to the accompanying drawings forming a part of this specification, it being understood that the drawings are merely illustrative of one example 25 of the invention.

Figure 1 is a longitudinal vertical section of a grate embodying my invention showing the grate bars at the limit of their rocking movement imparted by a rearward movement of the rocking means.

Figure 2 is a fragmentary view similar to Figure 1 but showing the grate bars at the extreme limit of the opposite rocking movement.

35 Figure 3 is a view similar to Figure 2 but showing the grate sections in the dumping position.

Figure 4 is a transverse vertical section.

Figure 5 is a fragmentary plan view, the 40 grids or firebed sections being omitted from the grate section at the right of the figure to show the grate bars and the swing frames supporting same.

Figure 6 is a transverse vertical section 45 on an enlarged scale given to show the grate bar and the supported grids or firebed sections.

Figure 7 is a section on the line 7—7 of Figure 6.

50 Figure 7^a is a section on the line 7^a—7^a of Figure 7 given to show the means for locking the grids to a grate bar.

Figure 8 is a perspective view of one of the cradles provided at the ends of the 55 swing frames for carrying the grate bars.

Figure 9 is a fragmentary perspective

view showing one end of the swing frame to which the cradles are secured.

Figure 10 is a perspective view of an end 60 portion of one of the grate bars.

Figure 11 is a fragmentary side elevation showing an end portion of the side frame bar.

In carrying out my invention in accordance with the illustrated example, longitudinal side frame bars 15 are provided and, if the grate be made in two sections, a central frame bar 15^a is employed also. The side frame bars have upstanding members or standards 16 and the central frame bar similar standards 16^a, which are formed with concave seats or bearings 17 (Figure 11), to receive end trunnions 18 on the upstanding ends 19 of swinging frames or bars 20. To the ends 19 of the swing bars 20 are secured 75 cradles 21, the ends 19 of the swing bars having lugs 22 on which the cradles rest and by which they are aligned, and bolts 23 secure the cradles on the swing bars, the bolts passing through bolt holes 19^a, 21^a. 80

In the upper edges of the cradles 21 are bearings or rests 24 for journal members 25 on the grate bars 26 which journal members, it will be noted, are inward from the ends of the grate bars for a purpose that will appear. The grate bars have rigid therewith inward of the journal members 25, shaker arms 27 which have journals 28 projecting therefrom in a direction away from the ends of the bar; that is to say, projecting laterally inward longitudinally of the grate bar. 85

The grate bars are rocked for shaking the grate and the swing frames 20 are rocked for dumping the grate through the medium of longitudinal reach rods 33—33^a, the one rod 90 operating the front series of grate bars and the other rod operating the rear series of grate bars as is usual. The groups of the grate bars of the front grate section or assemblage are operated independently of groups of the rear grate section as is customary and as shown in my patent above mentioned; therefore, separate reach rods 33—33^a are employed for the groups of the 95 respective grate sections. Said rods 33—33^a are operated by levers 34 to be hereinafter further referred to, and at their inner ends are respectively connected with the groups of grate bars of the respective grate sections as follows: It will be seen in Figure 1, there are two groups of three grate bars each in 100 the front grate assemblage or section, and

105

110

two groups of three grate bars each in the rear assemblage.

Each group of three grate bars has the journals 28 of the shaker arms 27 pivotally engaging a link 29, the depending end 29^a of each of which has a fork 29^b, and a pin 32 extends transversely through said fork and through the upstanding end 35 of a longitudinal link 36 which has depending ears 37 receiving the reach rod 33 or 33^a, a pin or bolt 38 passing through said lugs 37 of reach rod, completing the connection. Thus, two links 29 connect respectively with the ends of a link 36. The pin 32 passes also through a slot 31^a in an arm 31 on a plate 30, best shown in Figure 9, which has teeth on its upper surface mating with similar teeth on the under side of cross bar 20, there being a vertical pin 39 passing through said cross bar 20 and arm 31, the arrangement serving to adjust the total effective length of the arm 31 for a purpose that will appear. For operating a reach rod 33 or 33^a, the lever 34 has a slotted bracket 34^a thereon adapted to receive a pin 33^b on the reach rod and said lever bar at its lower end is adapted to be fulcrumed at different points for varying the amplitude of movement of the reach rod according to whether the grate bars are to be shaken or to be dumped. Thus a bracket 40 is provided on the front B of the furnace and has a transverse pin 41 adapted to be engaged by the fork 34^b on the lower end of bar 34; also pivoted to said bracket 40 is a link 42 having at the outer end a fulcrum pin 43 with which lever bar 34 also may engage.

With the described arrangement, if the lever bar 34 is fulcrumed on pin 43, the reciprocating movement imparted to the reach rod 33 or 33^a or said bar 34 will be such as to restrict the links 29 and 36 to an extent to give a shaking movement to the grate bars 26 through the medium of their shaker arms 27 and pins 28. On the other hand, if the lever bar 34 be fulcrumed on the pin 41, then the movement of the reach rod 33 or 33^a may be such as to cause the pin 32 to engage the rear end of the slot 31^a in arm 31 of cross bar 20 and said cross bar will thus be rocked on its trunnions 18 through an angle to swing the groups of grate bars 26 on the respective cradles 21 to the dumping position as indicated in Figure 3.

It will be observed that the shaker arms 27 of the grate bars 26 are inclined at the same angle to a vertical plane, the result of which is that the links 29 pivoted to the respective groups of grate bars will have parallel movements in the shaking of the grate bars so that the said links will be disposed horizontally in the shaking as in the normal position of the grate bars. When, however, an excessive movement is given to the reach rod 33 or 33^a for dumping the groups of grate bars, the two cross bars 20

associated with a given link 36 will be swung through an arc carrying with them the links 29 to the angular position shown in Figure 3. In the dumping movement of the cross bars and cradles with their groups of grate bars on the respective cradles, the links 36 remain in parallel relation to the actuating reach rods, while the links 29 assume the tilted or angular positions to conform to the swinging movements of the cross bars 20.

Numeral 44 indicates lugs on the frame bars 15 on which the cross bars 20 rest when in normal position. Numeral 45 indicates filler elements on the bridge wall 46 at the back of the grate bar. The character 26^a indicates fixed grate bars at the front of the firebed. To guide the grate bars 26 and prevent displacement thereof when rocking, the cradles 21 have arcuate lugs 47 which are accommodated in corresponding grooves 48 in the grate bars. The forward rocking movement of the grate bars is limited by stops 49, 49^a on the cradles. In the swinging movements of the cross bars 20, they are held against displacement by arcuate lugs 50 on the inner faces of the sides 19, said lugs being disposed beneath arcuate ribs 51 on the frame bars 15.

In order to prevent clinkers from wedging between the walls of the furnace and the ends of the grate bars, I provide clinker bars which may be formed of the upper and lower sections 52, 53, the latter being offset laterally inward and secured by bolt 54 or other means to frame bars 15. Supporting lugs 15^a are formed on the frame plates 15 to lie beneath the clinker bar section 53. The upper sections 52 may rest on the lower sections 53 and be readily renewable. The upper edges of the clinker bars have vertical slots 55 to minimize the bodily expansion and contraction of said bars.

Each grate bar 26 supports grids 56 detachably secured to the grate bars to form the firebed. Said grids present a broad area and preferably and advantageously the top surface thereof is rounded. Each grid 56 includes a plurality of crossing bars 57, 58. Also, each grid 56 has depending sides 59 which are formed with vertical slots 60 so that the grids may be dropped over the grate bars. The sides 59 of the grids 56 constitute standards sustaining the broad tops or grids proper at such an elevation as to lie above the journal ends 25 of grate bars 26 and above the journals 18 of swingable cross bars 20, to protect said ends 26 and journals 18 from the intense heat of the fire. At the same time ample clearance is afforded below the grids and journal members 25 for the movements of the shaking and dumping means. On the grate bars at each side of the slots 60 are ribs 61 which are positioned against the depending sides 59 to retain the latter. Adjacent sides 59 of adjacent grids

56 are locked to the grate bars to prevent vertical displacement of the girds, there being employed for the purpose in the illustrated example keys 62. The said keys 62
5 are passed transversely through recesses 63 in the ribs 61 and through recesses 64 in the sides 59 at the slots 60 whereby the key interlocks with both the said ribs 61 and said sides 59. The ends 62^a of the key, when the
10 key is in position, are bent into slots 65 in the grate bars 26. The character 61^a represents ribs corresponding to rib 61 but formed on the grate bar adjacent to the ends thereof beyond the journals 25 to receive a side 15
15 of a grid 56.

It is to be observed that the grids 56 extend in proximity to the side walls of the ash pit, being separated therefrom only by the narrow clinker bar sections 22. Thus,
20 the dead or fixed grate surface is minimized and practically eliminated as compared with the substantial dead grate area at the sides and center of rocking grates in use in furnaces, to which the invention pertains. The
25 increased effective grate area presented by the described grids is provided for by setting the side frame bars 15 farther from the side walls which arrangement is turned to advantage instead of being made to increase
30 the dead grate surface. A similar condition exists with respect to the central bar 15^a, the standards 16^a of which are materially separated to accommodate the projecting terminals of the grate bars. The advantages of
35 the arrangement referred to reside in an increased air circulation at the sides and center of the grate and also the arrangement permits of providing grate bars affording support for grids 56 at points on the bars near
40 the extreme ends thereof beyond the journal members 25. An important feature also is that the trunnions 25 of the respective grate bars 26 in addition to being located inward from the ends of the bar are offset above the
45 axis of the body of the bar, by reason of which the grids 56 supported on said bar will have their center of rocking movement so located that said grids will turn through arcs corresponding with their own radius
50 and be permitted clearance, as well as amplitude of movement in shaking and dumping,

without adjacent grids clashing one with another. At the same time the result is obtained that the grids will lie in close relation to one another when in normal position. 55

I would state in conclusion that while the illustrated example constitutes a practical embodiment of my invention, I do not limit myself strictly to the mechanical details 60 herein illustrated, since, manifestly, the same can be considerably varied without departure from the spirit of the invention as defined in the appended claims.

Having thus described my invention, I 65 claim:—

1. In a furnace grate, swingably mounted cross bars, grate bars above said cross bars and arranged parallel therewith, means supporting the grate bars for rocking movement 70 on the cross bars, reciprocating operating means pivotally connected with the grate bars for shaking the same, and members on the cross bars, said operating means having clearance in said members on the cross bars 75 in the shaking of the grate bars and engageable with said members by an excessive movement of said operating means for dumping the grate bars; together with means to adjustably secure said members on 80 the cross bars to regulate the clearance and engagement of the operating means with said members.

2. In a furnace grate, a supporting frame, cross bars swingably supported on said 85 frame, grate bars ranging parallel with the cross bars above the same, and means rockably supporting the grate bars on said cross bars, a reach rod, means connected with the grate bars for shaking the same and connected with said reach rod, said means being adapted also to engage the cross bars for swinging the same upon excessive movement of the reach rod, a lever bar for actuating said reach rod, and having means to detachably engage the latter, and means to fulcrum said lever bar at different distances 90 from the grate for varying the amplitude of movement imparted to the reach rod by said lever bar. 95

HENRY BENTON.
